MERCURY RECTIFIER

Clarence W. Hansell, Rocky Point, N. Y., assignor to Radio Corporation of America, a corporation of Delaware

Application April 18, 1936, Serial No. 75,069

4 Claims. (Cl. 175—363)

This invention relates to a new and novel mercury vapor rectifier having a mercury pool cathode combined with a heated or thermionic cathode in order to make the rectifier self-starting and to maintain the arc during operation.

An object of this invention is to provide an improved self-igniting rectifier and a circuit arrangement capable of handling a large amount of power.

Another object of this invention is to provide an external current limiting device in the heated cathode branch of the rectifier circuit to limit the rectified current in this branch to a value which is somewhat less than the limiting cathode emission.

Although mercury rectifiers are relatively old in the art, the mercury pool types require complicated ignition systems to start and maintain the arc and the thermionic or heated cathode type is limited in peak current rating by the electron emission from the cathode. This invention overcomes the above-mentioned limitations by the provision of both types of cathodes in a single rectifier with a circuit arrangement which provides for carrying the main rectified current to the mercury pool cathode and which provides for initiating the current or arc discharge with the aid of the relatively small heated cathode.

The invention will best be understood by referring to the accompanying drawing, which shows a schematic diagram of the improved tube and its associated circuit. In the drawing, the rectifier chamber 1 has the usual anode 2 and mercury pool cathode 4. A second cathode 3 is located in the rectifier chamber and it is designed to be heated to an electron emitting temperature by means of electrical heating. The cathode 3 may be a filamentary type, directly heated, or it may be indirectly heated. Also, it may be coated to reduce the required temperature for electron emission. In fact, any of the electron emitting cathodes commonly used in heated cathode gaseous rectifiers may be used. Current to the rectifier is supplied from an input alternating current source which is fed into a transformer 5 having a primary winding 6, a secondary winding 7 and a cathode supply winding 8. The filament winding 8 may have a midpoint tap 9 to which is connected cathode resistance 10. The output from the rectifier consists of a smoothing filter having inductance reactances 11 and 12 and filter condenser 13, the direct current load being indicated by resistance 14 which may be in the form of a voltage divider. Other filter

elements, metering, overload protection, etc., would, of course, be used when desired.

In the circuit as shown in the drawing, the heated cathode 3 is connected with the mercury pool cathode 4 through a resistance 10 which connects to the midpoint tap 9 of filament winding 8, the purpose of resistance 10 being to limit the rectified current to a value less than that of the cathode emission. In effect, the heated cathode 3 would serve to start the discharge in the tube, but after the discharge is started, then the mercury pool cathode 4 will carry the main part of the cathode current. Then, if there were sufficient energy dissipation rating to take care of the losses, a rectifier capable of handling a very large amount of power output would result.

In operation when thermionic cathode 3 is heated a discharge takes place between this cathode and anode 2. This discharge causes an ionization of the gas within the tube and thereby establishes the main discharge between the mercury cathode 4 and the anode 2. Since the thermionic cathode has a limited electron emission it is necessary that the current flow from this cathode to the anode be limited to prevent the cathode from being damaged by excessive heating and bombardment. The current flow in this path is limited by means of resistance 10 in series with the filamentary cathode and the output circuit. Alternatively, to assist in starting flow of current to the mercury pool cathode 4, I may place a direct current source 16 in series with the current limiting impedance 10. This direct current source may be a small rectifier, preferably of the copper oxide or similar type. It serves to make the mercury pool positive with respect to the heated cathode 3 and causes a flow of current between them. Electrons leaving heated cathode 3 strike the surface of the pool of mercury 4 and initiate a discharge from the pool 4 to the anode 2 by causing emission of secondary electrons from the surface. The action in this case may be improved by placing the cathodes relatively close together and by partially shielding cathode 3 from the electric field of the anode 2.

This invention should not be limited to the particular arrangement and/or circuit shown, as it is capable of taking other forms. For example, 3, 4, 6, 12, or other members of anodes may be used to provide polyphase rectification. The invention should only be limited to such limitations as are clearly imposed in the appended claims.

What is claimed is:

1. A rectifier circuit comprising an input

source, a transformer connected to said input, said transformer having a primary and a secondary and a cathode heating winding having a central tap, a rectifier having an anode, a heated cathode connected to said heating winding, and a second cathode comprising a mercury pool, one side of said secondary being connected to the anode of said rectifier, a direct current source, a resistance connected from said central tap to said direct current source and said second cathode of said rectifier tube whereby the current flow from said heated cathode to said anode is maintained within the emission capabilities of said cathode, the output of said rectifier circuit being connected to the other side of the transformer secondary winding and to the second cathode of the rectifier tube.

2. A rectifier circuit comprising an input source, a transformer connected to said input, said transformer having a primary and a secondary and a center-tapped filament winding, a rectifier having an anode, a filamentary cathode having a limited electron emission connected to said filament winding, and a second cathode comprising a mercury pool, one side of said secondary being connected to the anode of said rectifier, a resistance having such a value that the current flow from said filamentary cathode is maintained within the emission capability of said cathode, said resistance being connected from said central tap to said second cathode of said rectifier tube, the output of said rectifier circuit

being connected to the other side of the transformer secondary and second cathode of the rectifier tube.

3. A rectifier circuit comprising a source of alternating current, a load circuit and a rectifier having an anode and a mercury pool cathode within a casing, said source of alternating current, said load and said rectifier being connected in series, a heated cathode within said rectifier casing, a source of current for heating said heated cathode and an external resistance connected from said source of current for heating said heated cathode to said mercury pool cathode whereby the current flow from said heated cathode to said anode is maintained within the emission capabilities of said heated cathode.

4. A rectifier circuit comprising a source of alternating current, a load circuit and a rectifier having an anode and a mercury pool cathode within a casing, said source of alternating current, said load and said rectifier being connected in series, a heated cathode within said rectifier casing, a source of current for heating said heated cathode, a direct current source and an external resistance connected from said source of current for heating said heated cathode to said mercury pool cathode whereby the current flow from said heated cathode to said anode is maintained within the emission capabilities of said heated cathode.
